[57] CLAIM

The ornamental design for a mobile traffic signal, as
shown and described.

DESCRIPTION

FIG. 1 is a perspective view of a mobile traffic signal
showing my new design;

FIG. 2 is a front elevational view thereof;

FIG. 3 is a rear elevational view thereof;

FIG. 4 is a top plan view thereof;

FIG. 5 is a side elevational view thereof;
FIG. 6 is a side elevational view thereof in the collapsed
position;

FIG. 7 is a front elevational view of a second embodiment
of my new design, the second embodiment differing
from the first only in the shape of the top signal light
casing.

FIG. 1

FIG. 2

FIG. 3

FIG. 6

FIG. 5

FIG. 4

FIG. 7
